US0D1099722S

(12) **United States Design Patent** (10) Patent No.: **US D1,099,722 S**
(45) Date of Patent: ** Oct. 28, 2025

(54) **PHONE MOUNTED TRACKING DEVICE**

(71) Applicant: **Wanchen Kaiser**, New York, NY (US)

(72) Inventor: **Wanchen Kaiser**, New York, NY (US)

(**) Term: **15 Years**

(21) Appl. No.: **29/940,820**

(22) Filed: **May 6, 2024**

(51) LOC (15) Cl. **10-04**

(52) U.S. Cl. **D10/70**
USPC ....

(57) **CLAIM**

The ornamental design for a phone mounted tracking device as shown and described.

DESCRIPTION

FIG. 1 is a top front perspective view of a phone mounted tracking device showing my new design;

FIG. 2 is a top rear perspective view of the phone mounted tracking device showing my new design;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Portions of the phone mounted tracking device shown in even broken lines forms no part of the claimed design. The uneven broken lines depict boundary lines that form no part

(Continued)

of the claimed design. The light emitting diodes shown in FIGS. 1 and 3 are all the same shape and depth.
